UNITED STATES PATENT OFFICE.

WILLIAM C. ANDREWS, OF CLEVELAND, OHIO, ASSIGNOR TO HARRY A. AUER, OF CLEVELAND, OHIO.

METHOD OF PRODUCING GUN-BARRELS.

1,324,141.

Specification of Letters Patent.

Patented Dec. 9, 1919.

Original application filed January 21, 1916, Serial No. 73,355. Divided and this application filed January 11, 1917. Serial No. 141,744.

To all whom it may concern:

Be it known that I, WILLIAM C. ANDREWS, citizen of the United States, residing at Cleveland, in the county of Cuyahoga and State of Ohio, have invented certain new and useful Improvements in Methods of Producing Gun-Barrels, of which the following is a specification.

My invention relates to a new and improved method of producing a gun barrel in a rapid and efficient way, which consists in finishing the rough bore of a gun by a series of actions involving the use of various mechanisms but not confined to one, substantially as herein shown and described and more particularly pointed out in the claims. Heretofore the practice has been to roughly bore the barrel, that is, to drill a round opening lengthwise through the barrel to a predetermined diameter several thousandths of an inch less than the caliber of final desire. The next step or series of steps consisted in enlarging and smoothing the rough bore to the required caliber or diameter by a circular cross cutting action, using a rotary cutting tool or reamer, or by the successive use of a series of rotatable reamers of different sizes. Reaming operations involve the use of a special machine, proceed slowly, cause warping of the barrel necessitating straightening before rifling operations, and produce cuts or circular lines, ribs or scratches transversely in the finished bore. The next step involves rifling of the gun barrel; that is, a series of spiral grooves are produced longitudinally of the gun bore by a second machine employing a draw cutting or scraping tool. When the grooving operation is finished a series of narrow spiral lands have been developed upon which the cross cuts of reaming operations are often visible to the naked eye notwithstanding that the reaming operation is supposed to smooth the bore and does do so except for the defects noted. A final dressing operation is sometimes resorted to as a last step to cure the defects of reaming, but this in turn is detrimental to the land edges which should remain sharply cut to operate at their maximum efficiency in rotating the bullet in its course through the barrel. Having these old steps and results in mind, the object of my invention is two-fold, first, to produce an improved rifle barrel without objection-

able internal faults, and second to produce 55 a rifle barrel by simpler, speedier and more economical steps than as practised heretofore. That is to say, the steps taken by me eliminate the old reaming operation entirely and the objectionable cross cuts altogether, while the rifling and finishing operations of the bore may be performed in one and the same machine instead of separate machines as heretofore, and where the former practice was to enlarge the bore to its true 60 caliber as a first step and to rifle the enlarged bore as a second step, I prefer to reverse the sequence of actions by first rifling the barrel in its roughly-bored state, and secondly, enlarging and smoothing the rifled rough bore 65 to its true caliber. In effect, the finishing and smoothing of the rough bore is to enlarge the bore, which I accomplish by a series of cutting actions, each continuously applied on elongated spiral lines lengthwise 70 of the bore, and therefore I am enabled also to perform this finishing and enlarging operation of the bore during the final steps and stages of rifling on lines coinciding with the spiral grooves. That is, with one form of 75 tool which I may use the final steps of rifling the bore and the enlargement thereof to a predetermined smoothness and caliber proceed simultaneously. Such a tool is shown and described in my co-pending application, 80 filed January 21, 1916, Ser. No. 73355, of which this application is a division, but I do not restrict myself to the use of this specific tool in practising my invention. In fact, the method is not absolutely dependent 85 upon a machine or any particular tool, but as it is best illustrated and practised by mechanism, the accompanying drawings serve to show one form of mechanism with which to practice this method in general and 90 a specific mode of operation also.

Thus, in Figure 1, I show a plan view of a cutting tool or rifling head (substantially full size) entering one end of a gun barrel as at the start of operations. Fig. 2 illustrates an enlarged face view of a cutter adapted to produce a pair of grooves and a rifling land therebetween and having a cutting edge adapted to finish the face of the land. Fig. 3 is an enlarged longitudinal section of the tool on line 3—3, Fig. 8. Fig. 4 is an enlarged face view of a single-grooving cutter. Fig. 5 is a section longi-

tudinally of the tool in a plane at right angles to Fig. 3. Fig. 6 is a longitudinal section of a finished rifle barrel, Figs. 7 to 12, inclusive are transverse sections of a gun barrel and the tool on line $x-x$, Fig. 3, showing various stages in rifling and bore enlarging operations, as hereinafter more fully described.

The tool shown comprises a cylindrical head —A— which is of approximately the same diameter as the rough-bore of the gun barrel B so as to move freely therein, and this head is tubular and affixed to a rod 2 which is rotated and reciprocated simultaneously in rifling operations by automatic mechanism of any suitable character and kind known to those skilled in the art. That is, the tool is adapted to be used in any known machine for rifling gun barrels wherein the barrel is held stationary at intervals while cutting proceeds, and also rotated a definite number of degrees at intermittent intervals while the cutting tool is projected out of the barrel, these operations proceeding automatically as usual for the purpose of producing a series of collateral grooves and lands within the barrel according to any desired or accepted standard. For example, the present tool is designed to produce four grooves and lands, and the rod 2 is reciprocated and rotated automatically by the machine to produce a spiral cut of gradual inclination, the tool being given one revolution in approximately each ten inches of longitudinal travel thereof throughout the length of the gun barrel while the barrel remains fixed and stationary. Each spiral cut removes a very thin ribbon or shaving and is obtained by drawing the tool through the barrel until it emerges therefrom, and then the cutters are collapsed before returning the tool through the barrel to repeat the operation. Four such draw cutting movements of the tool and four rotative movements of ninety degrees each of the barrel produce four rifling grooves or channels of the same depth but this depth is only a fraction of the depth required as it is not desirable nor practicable to cut each groove the full depth in a single draw cut, notwithstanding that the full depth of such a groove is usually only several thousandths of an inch. Consequently, repeated draw cuts are made until the grooves reach the required depth, and to do this the cutters are expanded automatically subsequent to each complete revolution of the gun barrel and following the fractional cutting of four grooves of equal width successively to the same depth. The number of times that such operations are repeated is dependent upon the number and depth of the rifling grooves and lands desired, but the last series of cutting actions finish the faces of the spiral lands as well as

the spiral grooves, thereby enlarging the rough bore to the final caliber desired by a planing movement coinciding exactly in direction to the spiral grooves produced in the bore, in this way cutting all the contiguous surfaces of the bore on coinciding spiral lines, the spiral being relatively elongated or of extreme obtuse pitch.

In these operations, a pair of hook cutters 3 and 4 may be used and related in a particular way to produce a plurality of cuts in each draw stroke of the tool A an overlapping cuts as well in successive draw strokes, all without injury to the lands 5 produced in the barrel by such series of actions. Thus, in one form of tool the cutters 3 and 4 may be of equal width and each have a curved draw cutting edge 6 conforming to the extreme diameter of bore desired measured to the bottom of the rifling grooves. The width of such cutters is more or less dependent upon the width of the lands 5 or the number of lands to be produced, and in the tool shown, cutter 3 is provided with a longitudinal channel 8 in its face 7 corresponding in width to the land to be made, and the channel 8 extends into the vertical or undercut shoulder which is crowned at each side of the channel by the cutting edge 6. Accordingly the cutting edge in cutter 3 is stepped and of the same outline as the channeled surface 7, and the end edge at the base of the channel provides a land planing edge 6' at a point relatively nearer the center of the tool than the double groove cutting edges 6. Compared therewith, cutter 4 is plain or of regular curvature to produce a single groove, and in the tool shown these two cutters are confined within longitudinal slots 9 placed approximately one-hundred and thirty-five degrees apart measured center to center radially of the tool. Moreover, each cutter has a beveled end 10 to engage the undercut end 11 of its corresponding slot 9, and a spring stem 12 for each cutter extends lengthwise of each slot into bearing engagement with the socket end 13 of a spring-pressed plunger 14 which is adapted to slide within a round opening extending centrally through cylindrical head A. The coiled spring 15 which is sleeved over the reduced extension 16 of plunger 14 is backed by a cross pin 17 in head A, and a conical projection 18 is provided centrally within the socket end 13 of the plunger to hold the cutter stems 12 centrally in place. Each cutter member is also provided with a beveled face 19 opposite its cutting face 7, and these beveled faces 19 are opposed and engaged by the corresponding beveled surfaces 20 of a wedge member 21 reciprocally confined within the smooth round opening within the head A. An inward movement of wedge member 21 expands the cutters uniformly, that is, forces them outwardly radi-

ally of the head notwithstanding the resistance offered by the end seating relations of each cutter with the undercut ends 11 of slots 9. Such resistance is overcome by the 5 end thrust upon said cutter members and the yielding action of the spring-pressed plunger 14. The inward movement of wedge member 21 is limited by an enlargement 22 on the outer end of the round operating 10 stem 23 striking the squared extremity 24 of a split screw plug 25 which is adjustable longitudinally within the screw-threaded end of head A, and the inner extremity of this screw plug limits the outward or retiring 15 movement of the wedge member 21 relatively to the cutters when these are to be collapsed for the return or idle stroke of head A. The outward movement of wedge member 21 is effected by a projecting pin or 20 screw 26 located at the bottom of member 21 when a suitable stop or operating part in the machine is reached and engaged during reciprocal movements of the tool. This screw 26 works back and forth in a longitudinal 25 slot 27 at the bottom of head A and functions also to hold wedge member 21 from turning within the head. Undue play or looseness of head A is prevented within the bore of the gun barrel B during entering 30 and cutting operations by means of a pair of wire bow springs 28 socketed at their ends with a limited play within oppositely-inclined holes within the upper side of the cylindrical head A.

35 Now referring to Figs. 7 to 12, these views illustrate a series of steps in rifling a gun barrel with a tool as shown, whereby four spiral grooves and lands are produced, but it must be understood that complete 40 rifling is not performed in the single series of steps illustrated but that substantially the same cycle of operations is repeated many times to cut the grooves to their full depth and to plane and smooth the lands.

45 Thus beginning with the gun barrel in its roughly-bored state and omitting the usual step of reaming the bore in a separate machine, I insert the rifling head or tool A within the gun barrel and pass the tool 50 through the bore of the barrel with the cutters 3 and 4 collapsed, a condition and relationship of parts illustrated in Fig. 7. The tool is projected more or less beyond the end of the barrel, say substantially as 55 shown in Fig. 1, and the cutters 3 and 4 expanded by wedge member 21 and positioned to produce the first light cut while the gun barrel is held stationary and the rod 2 reciprocated and rotated simultaneously by the usual means found in any ordinary rifling machine. The first light cut is relatively not as deep as shown in Fig. 8, but this view serves to illustrate the 60 operation, which consists in grooving the rough bore of the barrel in a plurality of

places approximately one hundred and thirty-five degrees apart radially of the barrel, and in the present case cutter 3 at the left produces a double groove and leaves a rough land portion 5 centrally opposite 70 the longitudinal channel 8 in said cutter, while cutter 4 at the right forms a single groove *a* the full width of the cutter. Cutting at this depth proceeds the full length of the barrel and a thin shaving is removed by 75 drawing the tool through the barrel while rotating the tool at the same time the desired number of times to produce a spiral cut of gradual inclination relatively to the axis of the barrel. At the end of this movement, the 80 cutters are collapsed by retiring the wedge member 21 and the tool is returned to the opposite end of the gun barrel for the next cut, which does not begin however until the barrel B has been given a quarter turn 85 as indicated by the arrow in Fig. 8 and which turned position of the barrel is shown in Fig. 9 and may be effected by hand or mechanism.

With the parts related in this way a second cutting action proceeds as before, the 90 position of cutter 4 at the right producing a second wide groove *b* in the barrel at a point intermediate the first-made land portion 5 and the first-made wide groove *a* 95 and it should be noted that cutter 4 is wide enough and the turned position of the barrel sufficient to cause cutter 4 to overlap the right border of the divided groove which has been cut previously by cutter 100 3 and that the land portion 5 centrally within said divided or double cut *c* by cutter 3 is cleared by a safe margin from cutter 4 during the second cutting step as shown in Fig. 9. Manifestly, this second 105 cutting step involves the production of a second land portion 5 and a divided or double groove *d* by cutter 3 at the left, see Fig. 9.

The reciprocal movements of the tool and the collapsing and expanding movements of the cutters being understood, suffice to say that the third cutting step of the cutters is illustrated in Fig. 10, a position of parts established by rotation of the gun barrel 110 ninety degrees in the direction shown by the arrow in Fig. 9 and from the position of the barrel in that figure to the advanced position in Fig. 10. Here the land portion 5 of the divided groove *c* is advanced safely 115 beyond the reach of cutter 4 and the newly-made land portion 5 centrally in the divided groove *d* is also clear of said cutter 4 while at the same time said cutter is in overlapping cutting relation with both 120 grooves *c* and *d* to remove the stock completely between the land portions, the stock removed by cutter 4 being indicated at *e* 125 in Fig. 9. A third land portion 5 and divided groove *f* is also being cut by cutter 130

3 while this stock *e* is being removed by cutter 4, and cutter 3 now produces an overlapping cut also at one border of the groove *a* where it has been advanced within the 5 reach of said cutter 3, see Fig. 10. Three land portions 5 have been clearly defined and cut to their final width at this stage of operations, and a segment of stock *g* has been left undisturbed between grooves 10 *a* and *b*, see Fig. 10, from which the fourth land portion is produced in the next or fourth cutting step, see Fig. 11, where the barrel B has been given its last quarter turn following the completion of the cutting 15 step shown in Fig. 10. In Fig. 11, all four land portions 5 are shown and all the stock removed between such land portions to a uniform depth, cutter 4 in this last stage serving to remove the stock designated by *h* 20 in Fig. 10, and the cutter 3 removing the surplus stock *g* at each side of the fourth land portion 5 as explained.

In all these successive steps or cycle of operations for producing the four lands and 25 a fractional grooving cut of uniform depth between the lands, the circular surface of each land defined by the rough bore of the gun barrel is not engaged nor cut by the cutting edge 6' at the base end of the channel 30 8 in cutter 3, and it is not until these series of steps or cycle of operations have been repeated a number of times and the full depth or substantially the full depth and final cuts have been reached by expanding 35 the cutters repeatedly that such land surfaces are engaged and cut by the cutting edge 6' of cutter 3, see Fig. 12. Thus finally, each successive movement of the tool through the barrel effects a supplemental 40 cut lengthwise of the face of the spiral land, beginning with a planing action on the rough surface as found originally, and proceeding with successive planing and smoothing actions lengthwise of each land on 45 elongated spiral lines coinciding exactly with the collateral spiral grooves until the full depth of groove desired is reached and the true and desired caliber of bore is obtained. It follows also that the final cutting 50 steps involved in producing the spiral grooves and the enlargement and smoothing of the bore proceed simultaneously, and to reach the desired depth of groove and a predetermined caliber of bore the cutters 3 and 4 are expanded by degrees, preferably 55 after each cycle of operations as defined by four successive quarterly rotations of barrel B, such expansion being effected by a partial rotation of screw plug 25 through its squared extremity 24 and a step-by-step inward movement of wedge member 21. To obtain these results automatically the machine using this tool is designed to have a stop to engage the stem enlargement 22 of 60 member 21 and effect the inward movement 65

described and also means to engage and rotate the screw plug 25 the required degree and when needed, for example, at the end of each cycle of four quarterly rotative movements of the barrel, but the feed may be produced by hand instead of by mechanism. In fact, the machine operating parts and the tool described may be of any suitable kind and construction and have only been described in detail to more clearly define the mode of operation or steps involved. 70

Concisely stated, my method of producing a rifled gun barrel of a predetermined caliber consists primarily in planing all of the contiguous curved surfaces of the bore of the gun repeatedly on coinciding spiral lines of gradual inclination relatively to the axis of the bore until a predetermined caliber is obtained, regardless of any particular sequence of steps taken. In a more limited 80 sense, the invention consists in planing a series of collateral grooves to a predetermined width and depth spirally within a gun barrel and then planing the land faces between the grooves on spiral lines corresponding exactly with the spiral grooves until a predetermined caliber of bore is obtained. Still more specifically, the invention consists in planing a series of grooves 85 spirally within a gun barrel and simultaneously at some stage of this operation, 90 preferably the final stage, planing the land portions on corresponding spiral lines until a predetermined caliber of bore and depth of groove is obtained. Other steps 95 subordinate to the foregoing are also involved all as hereinbefore described in detail, but in every instance the product of my method is superior to the product of other methods in which reaming is an essential 100 step in that if there be any scratch, mark, or irregularity of cut in the bore that such scratch, mark or irregularity, whether infinitely small or plainly visible, shall extend longitudinally of the bore and coincide 105 with the spiral grooves or rifling instead of being at an angle or counter thereto to impede the course of a bullet and cause fouling of the gun in use. 110

What I claim is:

1. A method of rifling and smoothing a gun barrel bore, consisting in first planing rifle grooves in the rough bore surface of the gun barrel, and secondly, enlarging and smoothing the unplaned portions of the 120 rough bore to a predetermined caliber.
2. A method of rifling and smoothing a gun barrel bore, consisting in planing rifle grooves in the rough bore of a gun barrel and enlarging the rough bore to a predetermined smoothness and caliber concurrently. 125
3. A method of producing a rifled gun barrel bore of a predetermined smoothness and caliber, consisting in boring the gun 130

- barrel roughly to a given diameter and subsequently smoothly enlarging and rifling the rough bore to provide lands and grooves by a series of corresponding cutting actions 5 advancing on identical lines of spiral curvature longitudinally of the bore and involving the surfaces of both the lands and grooves.
4. A method of finishing the rough bore 10 of a gun barrel, consisting in planing all of the contiguous curved surface of the bore repeatedly on relatively elongated spiral lines until a predetermined caliber is obtained.
- 15 5. A method of finishing the rough bore of a gun barrel, consisting in planing contiguous segmental surface portions of the bore repeatedly on identical elongated spiral lines lengthwise of the bore until the entire 20 circular surface of the bore has been enlarged.
6. A method of smoothing and rifling a gun barrel bore, consisting in planing a series of radial grooves to a predetermined 25 width and depth spirally within the circular bore surface and then planing the radial land faces between the grooves on spiral lines corresponding exactly with the spiral grooves until a predetermined caliber of 30 bore is obtained.
7. A method of rifling and smoothing the rough bore of a gun barrel, consisting in planing the circular surface of the bore at different places radially thereof and successively until a series of grooves of a predetermined depth are obtained, the planing actions proceeding on identical spiral lines extending lengthwise of the bore and being repeated lengthwise of the remaining 35 40 unplaned surfaces of the bore until a predetermined smooth caliber is obtained.
8. A method of rifling and enlarging the rough bore of a gun barrel, consisting in removing a thin shaving from the rough bore 45 surface successively at different radial points of the bore by a cutting action proceeding lengthwise of the bore on parallel spiral lines and repeating said cutting actions until a series of grooves of predetermined depth 50 have been formed, and finally duplicating such cutting actions over the rough uncut segmental portions of the bore until a smooth rifled bore of predetermined caliber is obtained.
- 55 9. A method of rifling and enlarging the rough bore of a gun barrel, consisting in planing a series of grooves radially and spirally within the rough bore surface, and simultaneously planing the land faces between the grooves on corresponding spiral 60 lines until a predetermined caliber of bore and depth of groove is obtained.
10. A method of rifling and enlarging the rough bore of a gun barrel, consisting in grooving the circular surface of the rough 65 bore at different circumferential places therein simultaneously by a series of cutting actions moving on corresponding spiral lines longitudinally of the bore, and then planing the uncut segmental portions of 70 the bore surfaces by continuing said cutting actions until a smooth rifled bore of predetermined caliber is obtained.
11. A method of rifling the bore of a gun barrel, consisting in removing segmental 75 surface portions of the bore simultaneously in adjoining areas thereof by a double cutting action moving in a longitudinal direction on identical spiral lines, then repeating the same cutting actions with an overlapping cut in different radial places successively in the circular bore surface, and then continuing the spiral cutting action over the uncut segmental portions of the bore surfaces until a predetermined caliber 80 85 of bore is obtained.
12. A method of producing a rifled gun barrel of a predetermined caliber, consisting in planing the rough bore by successive planing actions moving lengthwise of the 90 bore on corresponding spiral lines and in a plurality of adjoining places simultaneously, continuing such cutting actions to different depths at different places in the circumference of said bore until a series of 95 spiral grooves and lands have been produced, and finally planing the land surfaces by similar cutting actions until a smooth rifled bore of a predetermined caliber is obtained.
13. A method of rifling a gun barrel, consisting in cutting a series of grooves spirally in the curved surface of the gun bore, by a series of successive cutting actions, each advancing on corresponding curved lines side 100 105 by side and limited to a fraction of the depth and width of groove to be produced, and each succeeding cutting action advancing in an overlapping relation to widen the groove previously cut.

Signed at Cleveland, in the county of Cuyahoga and State of Ohio, this 28th day of December, 1916.

WILLIAM C. ANDREWS.
